AUTOMOBILE DOOR CHECK

Rex C. Jacobs, Detroit, Mich., assignor to F. L. Jacobs Company, Detroit, Mich., a corporation of Michigan

Application May 25, 1935, Serial No. 23,352

6 Claims. (Cl. 16—82)

This invention relates to door checks particularly adapted for use on automobile doors, the primary object of the invention being to provide means for limiting the swinging movement of a hinged door so as to prevent damaging contact thereof with the adjacent parts of an automobile body when the door is moved toward its open position.

It is well known that when movement of a swinging door is abruptly stopped, such as by a positively functioning door check, stresses are set up in the door, the hinges supporting the door and the door jamb with the result that all of these parts are subject to strains and the hinges are liable to be torn from the jamb or from the door. Accordingly it is another object of this invention to provide a door check with cushioning means for limiting the swinging movement of a door, the purpose of the cushioning means being to avoid stopping the swinging movement too abruptly and to avoid the stresses and strains which result when the door is stopped too abruptly.

Another important object of the present invention is to provide a door check with yieldable means for holding a door in an open position.

Still another object of the invention is to provide a door check having one end adapted for connection to a door and the other end being adapted for connection to a door jamb, the means for connecting the check to the jamb having cushioning characteristics and being constructed so that in the event that an excessive pressure is being exerted on the door the connection with the door jamb may be severed without destroying any of the parts and without impairing their future use after they have been re-assembled.

With the above and other ends in view the invention consists in matters hereinafter set forth with reference to the accompanying drawing, in which—

Figure 1 is a fragmentary cross section of a door and door jamb with the present door check connected thereto;

Fig. 2 is a view similar to Fig. 1 with the door in an open position;

Fig. 3 is a fragmentary cross section of the door jamb illustrating another stage in the function of the door check, and

Fig. 4 is a cross section illustrating the connection of the door check to the door.

Like characters of reference are employed throughout to designate corresponding parts.

The numeral 1 designates a door jamb having an opening 2 therein behind which is mounted a

bracket 3 having a socket 4. The wall 5 of the socket 4 is provided with an opening 6. A door 7 is connected to the door jamb 1 by a hinge 8, the vertical edge 9 having lugs 10 struck outwardly therefrom and supporting a pin 11 to which one end of a spring metal ribbon 12 is attached. The ribbon 12 extends through the opening 6 in the socket wall 5 and has its end bent to prevent its being pulled through the opening 6.

The spring strip or ribbon 12 is bent to form a loop 13 at its end so disposed with respect to the normal run of the ribbon that the latter is non-tangential with the circumference of the loop at the point of juncture therewith. This particular disposition of the loop, with respect to the normal run of the ribbon, provides a shoulder 14 at the point of juncture. The loop 13 follows a regular curve and substantially describes a semi-circle which merges into an irregularly curved or more or less flattened portion 15. The irregularly curved part 15 terminates in an angularly bent portion 16 and a shoulder 17 is formed at the meeting angle of the irregularly curved part 15 and the angular part 16. The angular portion 16 has its extremity bent inwardly, or in other words, extending in a direction toward the normal run of the ribbon 12 to provide a guide part 18, and integral with the guide part is a spring finger 19 whose end projects through the opening 6.

When the door 7 is moved on its hinges from the position shown in Fig. 1 to that shown in Fig. 2 the ribbon or spring strip 12 and the spring finger 19 are drawn through the opening 6 until the guide part 18 strikes the wall 5. At the time the guide part 18 contacts with the wall 5 its end will project into the opening 6 and further movement of the door will cause it to slide over the edge of the opening as illustrated in Fig. 3. In order to permit this function the loop parts 13 and 15 must be flexed and their natural tendency to resiliently oppose such flexing initially retards movement of the door.

When movement of the door moves the ribbon so that it reaches the position shown in Fig. 2 the edge of the wall 5 at the bottom of the opening 6 will be disposed in the meeting angle 17 of the parts 15 and 16 so that the resilient pressure exerted by the loop yieldably retards movement of the ribbon in either direction. In the event that movement of the door is not finally checked when the parts reached the position shown in Fig. 2 the loop flexes from the shape shown in full lines to that shown in dotted lines so as to bring the shoulder 14 into engagement

with the wall 5 and the end of part 18 into engagement with the ribbon 12. The loop on the ribbon resiliently opposes movement from the full line to the dotted line position to such an extent that under ordinary conditions the door will be moving so slowly at the time its movement is finally checked that no damage will result.

The spring ribbon 12 is provided with an arcuate or curved shape and when the door is opened and the ribbon is placed under tension the ribbon tends to straighten. The spring, in resiliently opposing this tendency to straighten provides additional cushioning action in the retarding of movement of the door.

When the parts are in the dotted line position shown in Fig. 2 the loop is closed, by contact of the part 18 with the ribbon 12, and its natural flexibility is destroyed to a great degree. However, in the event of an excessive amount of pressure on the door at this time, that is to say sufficient pressure to destroy the hinges, the loop may compress and pull through the opening 6.

The spring finger 19 engages the lower edge of the opening 6 and urges the ribbon 12 into engagement with the upper edge of the opening so as to prevent rattling of the parts when the door is closed as shown in Fig. 1. The spring finger 19 has an additional function in that it resiliently opposes straightening of the ribbon 12 when the door is fully opened, thus providing greater strength in the cushioning means.

Although a specific embodiment of the present invention has been illustrated and described it will be understood that various changes may be made within the scope of the appended claims without departing from the spirit of the invention, and such changes are contemplated. For example, the description throughout refers to the part 1 as being the door jamb and the part 7 as being the door, but it is obvious that this order might be reversed so that part 1 represents a door and part 7 the door jamb.

What I claim is:—

1. A door check comprising resiliently flexible material having a retainer receiving means at one end, a yieldable enlargement at the other end of said check and adapted to engage the side walls of an opening to normally prevent the check being drawn through said opening, said enlargement being yieldable to the extent that it becomes compressed in the presence of extraordinary pressure whereby it passes through said opening and resilient to the extent that it returns to its original form after it has passed through said opening.

2. A door check comprising resiliently flexible material having a retainer receiving means at one end, a yieldable enlargement at the other end

of said check and adapted to engage the side walls of an opening to normally prevent the check being drawn through said opening, said enlargement being yieldable to the extent that it becomes compressed in the presence of extraordinary pressure whereby it passes through said opening and resilient to the extent that it returns to its original form after it has passed through said opening, said check also having yieldable shoulders between said retainer receiving means and said yieldable enlargement adapted to engage the side walls of said opening as said check is drawn therethrough.

3. A door check comprising a flexible element having retainer receiving means at one end thereof, said flexible element having a resilient loop at its other end, and a plurality of shoulders formed at opposite ends of said loop, said shoulders being disposed whereby they consecutively engage different walls of an opening as said check is drawn therethrough.

4. A door check comprising a flexible element having retainer receiving means at one end thereof, said flexible element having a resilient loop at its other end, a plurality of shoulders formed at opposite ends of said loop, said shoulders being disposed whereby they consecutively engage different walls of an opening as said check is drawn therethrough, and means on the end of said loop for engaging said flexible element after a predetermined flexing of said loop for rigidifying said loop.

5. A door check adapted to be drawn between opposite side walls of an opening in a body, said check comprising a flexible element, retainer receiving means at one end of said flexible element, a resiliently flexible loop on the other end of said flexible element, a retaining portion integral with said loop and adapted to engage a wall of said opening, and a guiding surface adapted to enter said opening and engage a wall thereof to compress said loop when said check is drawn through said opening.

6. A door check adapted to be drawn between opposite side walls of an opening in a body, said check comprising a flexible element, retainer receiving means at one end of said flexible element, a resiliently flexible loop on the other end of said flexible element, a retaining portion integral with said loop and adapted to engage a wall of said opening, a guiding surface adapted to enter said opening and engage a wall thereof to compress said loop when said check is drawn through said opening, and a spring finger at one end of said guiding surface and adapted to yieldably engage a wall of said opening to prevent rattling of the check therein.
